UNITED STATES PATENT OFFICE

WILLIAM L. COULTAS, OF SEAFORD, NEW YORK

PROCESS FOR BURNING OIL

Application filed July 30, 1927. Serial No. 209,462.

This invention relates to methods for burning liquid fuel, and more particularly to oil burners adapted to be used in house heating plants, although adapted for use in steam power plants, industrial processes, and for other purposes, where fixed or variable temperatures are to be maintained automatically or otherwise.

It is desirable that oil burners which are to be used for such purposes be capable of burning relatively cheap fuel oil or other combustible oils and that they shall operate efficiently over a wide range of temperatures. Particularly where the apparatus is used for domestic heating, it should be capable of being put into operation easily, require a minimum amount of attention thereafter and be easily or automatically adjustable to meet the heating requirements made necessary by sudden changes in the temperature or of weather conditions. It should be clean in operation, free from all fire hazards and free from noise. Since the designs of household furnaces and boilers vary widely, the oil burning apparatus should be adapted to be used in connection with many different designs of boilers and furnaces.

The oil burning apparatus illustrated and described herein embodies these features and has for its principal object the provision of means for vaporizing heavy oils such as fuel oils and other liquid fuels, at atmospheric pressure or slightly less than atmospheric pressure, gasifying the vapors, mixing air therewith to form a combustible mixture, igniting the mixture out of contact with the fuel and discharging the same into the combustion chamber of a furnace.

Another object of the invention is to produce a continuous combustion while readily controlling the rate of vaporizing the fuel oil to meet the varying requirements of heat to be supplied by the apparatus.

A further object of the invention is to pro-

vide a thorough mixing of the air with the oil vapors in the presence of the liquid fuel while preventing explosive ignition of the vapors or liquid fuel or subjecting the same to temperatures above that of vaporization. 50

A still further object of the invention is to provide for the vaporizing of the lighter fractions of the oil and for burning the same above a flameless zone and out of contact with the fuel in order that the heat of the flame may 55 vaporize the heavier fractions of the oil without direct combustion thereof.

A further object is to provide a method for mixing the air and oil vapors in a separate zone out of contact with the fuel being vaporized so that the air and oil vapors are 60 thoroughly mixed before being introduced into the combustion chamber and then discharged into the fire box.

A further object of my invention is to provide a method and means for burning fuel oil to which my improved regulator, described and claimed in my prior patent No. 1,419,025 of June 6, 1922 as a "Feeding device", is especially applicable, as will be hereinafter 65 pointed out.

A still further object of my invention is to provide method for burning a supply of liquid fuel without first gasifying said fuel.

Briefly, the principal features of the invention may be described as follows: A supply of fuel oil is maintained in a suitable reservoir located within an enclosure adjacent to a vaporizing chamber having one end open as an air inlet and having the opposite end connected with a combustion chamber provided with a delivery conduit for discharging the burning gases into the fire box of the furnace or boiler. Jets of superheated steam at a temperature ranging from 1200° Fahrenheit 75 to higher temperatures are caused to impinge upon the surface of the liquid fuel in the reservoir. By numerous trials it has been 80 found that the apparatus operates most efficiently when the angle, in a longitudinal 85

plane, between the steam jets impinging upon fuel and the surface of the fuel in the reservoir is approximately 50°. These jets of superheated steam striking the surface of the oil cause the lighter fractions thereof to be vaporized and at the same time through the action of a deflector cause the resulting vapors to have an upward movement away from the surface of the fuel in the reservoir. The steam jets also draw in air through the air inlet and cause it to be thoroughly mixed with the vaporized fuel oil. The liquid fuel in the reservoir is maintained, by the superheated steam and by radiation from the flame at temperatures ranging from that necessary to produce vaporization of the lighter fractions of the oil to that producing vaporization of the heavier fractions without causing destructive distillation.

The vaporizing chamber is provided with an inclined deflector referred to above along the surface of which the vapors of the fuel oil are forced upward by the action of the steam jets. The upper portion of the deflector is curved so as to impart a rotary motion to the vapors of the fuel oil as they leave the upper edge of the deflector. A portion of this deflector is maintained at a temperature sufficiently high to convert the fuel oil vapors into fixed gases. The upper edge of the deflector is heated to a temperature of approximately 1200° F. which aids in igniting the mixture of inflammable gases and air.

The shape and the relative position of the deflector with respect to a projection between the roof of the vaporizing chamber and that of the combustion chamber are such that some of the mixture which is ignited at the top edge of the deflector passes into the combustion chamber while the remaining portion thereof is deflected into the vaporizing chamber as described above. The jets of superheated steam form a blanket between the fuel and the flame preventing the flame from contacting with the liquid fuel in the reservoir, but permit radiation of heat from the flame above the fuel. The burning gases are introduced into the vaporizing chamber for the purpose of preheating the oil vapors and the air and to vaporize the heavier fractions of the fuel oil without causing it to ignite or be subjected to destructive distillation.

It will be observed that by the above process the liquid fuel is vaporized and the vapors thereof are converted into fixed gases which after being mixed with heated air are ignited and discharged into the fire box of a furnace. By varying the depth of oil in the reservoir and consequently the surface exposed and by varying the temperature and the amount of steam supplied to vaporize the oil, the rate of vaporizing may be readily controlled.

It will be readily understood by one skilled in the art that by varying the location and di-

rection of the steam jets, steam may be impinged upon the body of the oil without forming such a protective blanket as described above. This positioning of the steam jets enables combustion to take place directly from the surface of the oil without first gassing the same if it be so desired.

The invention will be more fully understood from the following description taken in connection with the accompanying drawings and its scope will be pointed out in the appended claims.

In the drawings illustrating the invention, Fig. 1 is a schematic drawing showing how the various parts of the apparatus are connected together and, by means of arrows, indicating the directions in which steam and oil are flowing in various parts of the system; Fig. 2 is a cross-sectional view taken through the vaporizing and combustion chambers showing the shape of the vaporizing chamber and also showing the direction of the flow of the vapors and gases through this chamber; Fig. 3 is a partial cross-sectional view taken through the jet producing steam boiler and the vaporizing and combustion chambers showing the steam superheater pipes located in the combustion chamber.

In the drawings, the numeral 1 indicates a small steam boiler in which the steam used to form jets above the fuel oil in the reservoir, is generated. This boiler should have a capacity of one or two quarts of water only and is preferably located mainly above the combustion chamber 3 as indicated more clearly in Figs. 2 and 3. The boiler may thus be supplied with heat from the burning gases as they pass through the combustion chamber on their way to the fire box of the furnace. The boiler 1 is supplied with water from a water feeder 4 which is connected with a suitable supply of water by means of the pipe 5. The water flows from the water feeder 4 through the pipe 6 into the lower portion of the boiler 1 as indicated clearly in the drawings. The supply of feed water to the boiler is controlled by means of a suitable float valve located within the water feeder 4. The construction of such a float actuated valve is well known and need not be further described. The water feeder 4 is connected with the boiler 1 by an equalizing pipe 9 by means of which the pressure in the water feeder is made substantially the same as the pressure in the steam space of the boiler 1. The purpose of this construction is to assist the flow of water from the water feeder 4 through the pipe 6 into the boiler 1. A pipe 10 is connected with the steam space of the boiler 1 and steam flows therethrough into a superheater 11 positioned within the combustion chamber 3 as shown in Figs. 2 and 3. The steam, after thus being superheated, flows into a manifold 12 positioned within the vaporizing chamber 2. The manifold 12 is pro-

vided with a series of nozzles in its lower surface, as indicated in the drawings, so positioned as to direct the steam flowing there-through at a longitudinal angle with the 5 surface of the oil in the reservoir 13. It has been found that the apparatus works most efficiently when the angle between the steam jets and the surface of the oil is approximately 50°, although said angle may be varied de- 10 pending upon conditions existing in partic-
ular installations.

The reservoir 13 is located directly below the vaporizing chamber 2 as shown in Figs. 2 and 7 and is preferably in the form of a 15 shallow trough having its sides inclined as shown, whereby the surface area of the supply of fuel varies with the depth of fuel in the reservoir. The forward end of the reservoir 13 is provided with an inclined deflector 20 14, the main portion of which is preferably at an angle of about 50° with the surface of the fuel and the upper portion of which is curved as indicated at 15. The upper portion of the deflector is curved for the pur- 25 pose of imparting an upward rotary motion to the vapors flowing along the surface of the deflector as described above. The upper portion 15 of the deflector 14 also forms a kind of bridge wall over which some of the vapors 30 pass after being directed upward. A V- shaped projection 16 is provided so that the vapors flowing along the deflector 14 are caused to divide, some going into the combustion chamber 3 and some being returned to 35 the vaporizing chamber 2. The roof of the vaporizing chamber 2 is arched, as shown clearly in Figs. 2 and 3, for the purpose of assisting the rotary motion of the burning vapors. Air is supplied to the vaporizing 40 chamber 2 through the air inlet port 17.

The forward end of the combustion chamber 3 is provided with a funnel-shaped passage 18 through which the burning gases are discharged into the fire box of the furnace or 45 boiler.

Fuel oil which has been previously filtered is supplied to the reservoir 13 according to the amount of heat required from the apparatus. Suitable means are provided to drain 50 the oil from the reservoir 13 quickly when it is desired to extinguish the burner and these means are also adapted to furnish an initial supply of oil when starting the burner.

The operation of the apparatus may be de- 55 scribed as follows:—

The pool of oil in the reservoir 13 is ignited preferably by means of a small asbestos torch saturated with fuel oil. The flame of the torch ignites the more volatile vapors 60 which come in contact with the deflector 14 and heats it to the higher vaporizing tempera-
ture of the fuel oil. The flame from the burning oil and vapors heats the boiler 1 and generates steam preferably at a pressure of 65 about $\frac{1}{4}$ of a pound, which flows through the

superheater 11, to the manifold 12 then through the jets therein where it impinges on the oil in the reservoir. The flame, super- heated steam and oil vapors are then driven up the surface of the deflector 14 heating it 70 to a still higher temperature. As this mixture of flame, steam and vapors reaches the top of the deflector, some of the mixture flows over the deflector or bridge wall 15 into the combustion chamber 3, while the remain- 75 ing portion of the mixture is turned back into the vaporizing chamber 2 by means of the curved projection 16 at the upper portion of the chamber 2.

As more steam is generated in the boiler, 80 the steam impinging from the jets in the manifold 12 onto the oil in the reservoir 13 causes the flame to be driven from the sur- face of the oil to the upper portion of the vaporizing chamber 2. Thus after the appa- 85 ratus has been put into operation, the hori- zontal blast of steam causes a non-burning layer to be formed and the flame to be entire-
ly separated from the oil in the reservoir. Since the temperature of the oil heated by the 90 heat produced by the flame above ranges from about 450° to about 560° F., it is not subjected to destructive distillation nor is it ignited.

The temperature of the combustion cham- 95 ber 2 continues to rise until it is between 1200° and 1360° F. The steam is therefore super- heated to temperatures of approximately the same degree and is sufficient to vaporize the oil in the reservoir. The vapors being thoroughly mixed and subjected to the high 100 temperature in the vaporizing chamber 2 and on the surface of the heated deflector 14 are converted into fixed gases.

Air is drawn in through the inlet 17 by the action of the steam jets and after being 105 thoroughly mixed with the fixed gases the mixture ignites at the bridge wall 15 of the deflector with a clear and transparent gas flame. The burning gases flow from the combustion chamber 3 through the discharge nozzle 17 into the fire box of the furnace.

The rate of combustion of the fuel oil is preferably automatically controlled accord- 115 ing to the requirements for the heat demand-
ed of the furnace by varying the amount of oil supplied to the reservoir 13. This raises or lowers the surface of the oil in the reser-
voir and increases or decreases the exposed 120 surface area of the oil and correspondingly changes the rate at which vaporization will occur.

Having thus described this form of my in- 125 vention, I do not wish to be understood as being limited to details of form or the precise arrangement of parts set forth above, for various changes may be made by those skilled in the art without departing from the spirit and scope of my invention.

What I claim is:—

1. The process of burning liquid fuel 130

which comprises, maintaining a pool of said fuel, vaporizing a portion of the fuel in said pool, mixing air with said vapors, burning a portion of said mixture above, but out of contact with said pool to vaporize the remaining portion of fuel in said pool, removing the other portion of said mixture to and burning the same where the heat generated by said process is to be utilized.

10 2. The process of burning liquid fuel which comprises, maintaining a pool of said fuel, impinging superheated steam upon the surface of said fuel to vaporize a portion of the fuel in said pool, mixing air with said vapors, burning a portion of said mixture above, but out of contact with said pool to vaporize the remaining portion of fuel in said pool removing the other portion of said mixture to and burning the same where the heat generated by said process is to be utilized.

15 3. The process of burning liquid fuel which comprises, maintaining a pool of said fuel, impinging jets of superheated steam angularly on the surface of said pool to vaporize a portion of the fuel in said pool, mixing air with said vapors, said vapors and air being thoroughly mixed above the surface of said pool by said jets of superheated steam rebounding from the surface of said pool, burning a portion of said mixture above, but out of contact with said pool to vaporize the remaining portion of fuel in said pool, removing the other portion of said mixture to and burning the same where the heat generated by said process is to be utilized.

20 4. The steps in the process of preparing liquid fuel for combustion which comprise, maintaining a pool of said fuel, vaporizing a portion of the fuel in said pool and burning said vapors above, but out of contact with said pool by maintaining a non-burning layer of vapor on the surface of said pool, to vaporize the remaining portion of the fuel in said pool.

25 5. The steps in the process of preparing liquid fuel for combustion which comprise, maintaining a pool of said fuel, impinging superheated steam upon the surface of said pool to vaporize a portion of the fuel in said pool, maintaining a layer of rapidly flowing steam on the surface of said pool and burning said vapors above said layer of steam to vaporize the remaining portion of the fuel in said pool without igniting said pool.

30 6. The process of burning liquid fuel which comprises, maintaining a pool of said fuel, impinging superheated steam upon the surface of said pool to vaporize a portion of the fuel in said pool, mixing air with said vapors, burning a portion of said mixture above but out of contact with said pool to vaporize the remaining portion of fuel in

said pool removing the remaining portion of said mixed air and vapors and conducting the same to a point where the heat generated by said process is to be utilized, and utilizing the heat of the combustion of the said removed portion of said mixture to generate and superheat said steam.

Signed at New York, N. Y., this 27th day of June, 1927.
